UNITED STATES PATENT OFFICE.

ROBERT K. WITZ, OF CHICAGO, ILLINOIS.

ELECTRIC BINDING-POST.

1,164,440.

Specification of Letters Patent.

Patented Dec. 14, 1915.

Application filed July 1, 1911. Serial No. 636,498.

To all whom it may concern:

Be it known that I, ROBERT K. WITZ, citizen of the United States, residing at Chicago, in the county of Cook and State of Illinois, have invented certain new and useful Improvements in Electric Binding-Posts; and I do hereby declare the following to be a full, clear, and exact description of the invention, such as will enable others skilled in the art to which it appertains to make and use the same.

This invention relates to a novel construction in an electric binding post, the object being to provide simple and efficient means for enabling electric conduit wires to be secured thereto without necessitating the usual manipulation, such as bending a hook at the end of the wire to be attached and then engaging the same with the set screw of the binding post.

The invention consists in the features of construction and combinations of parts hereinafter fully described and claimed.

In the accompanying drawings illustrating the invention, Figure —1— is a view in side elevation partly broken away of an incandescent electric lamp socket equipped with binding posts constructed in accordance with my invention. Fig. —2— is a fragmentary detail central longitudinal section of the same on an enlarged scale on the line 2—2 of Fig. —1—, the shell of the socket being omitted. Fig. —3— is a fragmentary detail view in elevation of the binding post as formed in lamp sockets, plugs and similar electric devices. Fig. —4— is a view in side elevation of a binding post such as is used on switch boards, electric bells and the like, constructed in accordance with my invention, the plate to which said post is secured being shown in section. Fig. —5— is a detail sectional view on the line 5—5 of Fig. —4—.

My invention has for its particular object to provide simple and efficient means for winding the ends of wires about the screw of the binding post between the head of which and an opposing member such wire ends are intended and adapted to be clamped so as to avoid the necessity of first bending the hook on the wire and then engaging the shank of the binding screw therein as is usually requisite in effecting binding post connections. This operation is very frequently attended with considerable difficulty especially in such structures as incandes-

cent electric lamp sockets, plugs and similar devices, in which the space occupied by the binding post is extremely limited and the latter relatively difficult of access.

In Fig. —3— I have particularly illustrated the binding post of an incandescent electric lamp socket such as is ordinarily and most generally employed in the United States. Said binding post consists of a flat strip A of metal, such as brass or copper, which is provided with a threaded opening in which the shank B of the set screw for securing the wire ends to said binding post is engaged, the wire being adapted to be clamped between the head C of said screw and a portion of said strip or bar A. The latter is usually bent upwardly on either side of the opening for the passage of said shank B and, as shown in Fig. —2—, the said portion of said bar A containing said screw is disposed in a recess D in the porcelain body E of the socket, or other device, thus rendering the operation of engaging the end portion F of an electric wire G between the head C of said screw and the opposing portion of the strip or bar A a matter of considerable difficulty. To render this a matter of great ease and convenience is the object of this invention and is accomplished by providing in said shank B of the screw, immediately underneath the head C thereof, an opening H for the passage of the wire end to be engaged by said binding post. The said opening H is of a diameter amply large to receive an electric wire of the gage usually employed for this class of work so as to render the insertion of a wire end therein a matter of ease for the operator. After such insertion of said wire end the said screw is rotated by means of a screw driver in the ordinary manner thus winding the end portion of the wire rearwardly of that portion which is contained in said opening H around said shank and as the latter during such rotation passes farther through the threaded opening in which it is engaged the head C of said screw is brought to bear upon the wire thus firmly clamping the same against the opposing portion of the strip or bar A, as will be apparent. In affecting this connection the screw is preferably primarily turned so as to necessitate giving it one or one-and-one-half turns in the opposite direction for the purpose of bringing the head thereof into clamping relation to the

interposed wire end depending, of course, upon the nature of the connection and the need of providing sufficient surface contact between the wire and the binding post to 5 reduce resistance at this point to a minimum.

While my invention is particularly adapted to the binding posts of electric lamp sockets, plugs and the like, which are not 10 readily accessible, it is also very well adapted for use on switch boards for controlling high pressure currents where the operation of attaining wire ends is frequently attended with great danger to the operator. 15 In Fig. 4—I have shown a binding post of this character in which the screw I is provided immediately below the head thereof with an opening J passing through the shank and in which a wire end is adapted to 20 be received. The latter is maintained straight and is inserted by the operator into said opening J, the operator holding said wire on an insulated part thereof and with his other hand manipulating the screw 25 driver for turning said screw I. The screw driver being provided with a wooden handle is substantially insulated and as the operator is not obliged to touch the exposed portion 30 of a live wire with his other hand in effecting a connection it will be obvious that slipping of the screw driver and the contact of the metallic portion thereof with another live terminal will not endanger the operator. 35 At the same time in turning the screw I a very neat connection is made between the wire and the binding post.

The binding post constructed in accordance with my invention affords the further advantage of providing very much greater surface contact between the wire and the 40 binding post than is ordinarily provided in devices of this character.

The invention is very simple and efficient and affords a means of effecting great economy in the time required to make connections besides rendering the operation safe under conditions where heretofore it was 45 frequently relatively unsafe.

I claim as my invention:

An electric binding post comprising a base 50 member having a screw-threaded aperture therein with a plain flat contact surface surrounding said aperture, an externally threaded binding screw formed with a disk-shaped head having a flat under side extending parallel with the surface surrounding the aperture in said base member and adapted to coact therewith to impinge against opposite surfaces of a wire inserted 55 between said parts, said screw-threaded member being formed with a transverse perforation immediately beneath its head for receiving the end of the wire, substantially as set forth.

In testimony whereof I have signed my 60 name in presence of two subscribing witnesses.

ROBERT K. WITZ.
